[57] CLAIM

The ornamental design for a mop head, as shown and described.

DESCRIPTION

FIG. 1 is a front elevational view of a mop head showing my new design, wherein the rear elevational view is identical; FIG. 2 is a right end elevational view of the design of FIG. 1;

FIG. 3 is a top plan view of the design of FIG. 1; FIG. 4 is a bottom plan view of the design of FIG. 1; FIG. 5 is a left end elevational view of the design of FIG. 1;

FIG. 6 is a front elevational view of an alternate embodiment of a mop head showing my new design, wherein the rear elevational view is identical, and wherein the top plan view is identical to that shown in FIG. 3, and wherein the bottom plan view is identical to that shown in FIG. 4;

FIG. 7 is a right end elevational view of the design of FIG. 6; and,

FIG. 8 is a left end elevational view of the design of FIG. 6.
